RAILROAD CROSSING GATE

Filed Aug. 20, 1936

UNITED STATES PATENT OFFICE

2,126,548

RAILROAD CROSSING GATE

Harry R. Gilmore, Steubenville, Ohio

Application August 20, 1936, Serial No. 97,068

3 Claims. (Cl. 39—1)

This invention relates to improvements in railroad crossing gates, and pertains more particularly and specifically to such an installation in connection with city street railroad crossings, but

5 it is to be understood the present invention can be used equally as well in connection with rural railroad crossings.

The primary object of the invention is the provision of a new and improved railroad crossing gate.

A further object of the invention is the provision of a new and improved railroad crossing gate so designed as to protect pedestrians as well as vehicular traffic.

15 Another and still further object of the invention is the provision of a new and improved railroad crossing gate which is automatic in operation; which gives warning of the approach of a train as well as warning of the closed position of the gates; and provides automatic means for taking pictures of any vehicle which might contact the gates when the same are in a closed position.

20 Other further objects, novel features of construction and improved results of the present invention will appear in more detail from the following description when read in the light of the accompanying drawing.

In the drawing which illustrates a preferred embodiment of the present invention:

25 Fig. 1 is a view in elevation of the gates at one side of the railroad or car tracks.

Fig. 2 is a vertical sectional view taken on the line 2—2 of Fig. 1, looking in the direction indicated by arrows.

30 Fig. 3 is a diagrammatic or schematic showing of the electric installation and the manner of providing gates at a plurality of street crossings.

Fig. 4 is a detailed view, partly in section, illustrating the engagement between a closed gate and the bumper of a motor vehicle.

35 Referring now to the drawing in which like parts are designated by similar reference letters and numerals throughout the description and with the understanding that the gates at one side of the tracks only are illustrated and described, because the gates at the other side of the tracks are identical in construction and operation, it will be seen that a pair of vertical extending standards 1 and 2 are provided at each side of the street 40 40 adjacent the curbing of the sidewalks 4 and 5 and that a cross arm or head 6 extends across the upper ends of said standards.

45 These standards are placed a considerable distance in front of the tracks and the standards are 45 of sufficient height to give adequate clearance for

the passage of traffic under the cross bar or head 6, as well as under the horizontally disposed and rotatably mounted shaft 7 which extends across the street and also the sidewalk.

The shaft 7 is rotated by means of electric motors 8 and 9 which have driving engagement with the gears 10 and 11 secured to the shaft. The manner and time of the operation of the motors 8 and 9 will hereinafter more fully appear.

A plurality of gates A, B, C, D and E are suspended from the shaft 7 and these may be made of vertical and horizontal cross chains or could be in the form of any suitable metallic mesh. The gates A and E are positioned above the sidewalks 4 and 5, and at their bottoms terminate in cushion bars 12. These bars carry a series of red lights 13. When the shaft 7 is rotated to lift the gates the gates A and E roll up upon the shaft between the guides 14 and 15.

45 As clearly indicated in the drawing, three gates 20 are used above the roadway and the gate B is above the left side of the roadway; the gate D above the right side of the roadway, and gate C above the center of the roadway.

50 At their bottoms these gates are provided with cushion bars 16 which are nine inches above and parallel with the highway. In spaced relationship along these bars are positioned steel hooks F, the upturned ends 17 of which are disposed to face traffic approaching the gates. These hooks 30 preferably terminate nine inches above the roadbed of the highway. Flange wheels or plates 18 are provided for guiding these three gates when they are rolled up upon the shaft 7. For the purpose of warning at night the closed position of 35 the gates their cushion bars are provided with a series of red lights 19.

55 Positioned adjacent and paralleling the vertical standards 1 and 2 are tubular guideways 20 in which the weights 21 are adapted to move. 40 These weights are each provided with a cable 22 trained over and having an attachment to a pulley 23 which has driving connection with the shaft 7. It is to be understood that when the gates are down these weights act as a reversing 45 mechanism to rotate the shaft 7 and lift the gates by winding them upon the shaft. This, of course, takes place after the delivery of current to the motors 8 and 9 has been discontinued, as will be hereinafter described. Upward movement of the 50 weights is limited by the stops 21a.

60 The gates A and E above the sidewalks will prevent pedestrians from entering upon the railroad tracks, while the gates B, C, and D will prevent vehicles from entering upon the tracks. Should 65

a vehicle, such as an automobile, attempt to pass the gates when they are down the front bumper of the car would strike against the gates and cause them to swing up as illustrated in Fig. 4, 5 where it will be seen that the hooks F engage the under side of the vehicle bumper G. The momentum of the vehicle will cause the gates to swing inwardly with the shaft 7 as the pivot point of their arc with the result that the front end of the 10 car is lifted forwardly and upwardly and will cause the rear end of the car to drag to a quick stop and thus protect the car passengers from injury.

In Fig. 3 I have shown schematically the preferred manner of installing my equipment. Here 15 three streets 1st, 2nd and 3rd are shown. The railroad tracks are shown at H and it is to be understood that at the meeting of each street and tracks there will be a gate such as has been described. The gates work in a unit of three by 20 which I mean the first portion of the cycle of operation of a gate begins two blocks or two streets ahead of the gate. Paralleling each set of railroad rails are three electric wires 25, 26 and 25 27. The wires at one side are for controlling the gates at one side of the tracks and the wires at the other side are for the purpose of controlling the gates at opposite side of the track. A description of the wires at one side of the track 30 will serve to describe both sets of wires. The wire 27 is a ground wire, while the remaining wires constitute the live electric current.

The electric current is such that in the event of the approach of a train in either direction 35 that the train upon reaching the street two blocks away will cause the bells 28 mounted upon the gate cross head, to ring and will cause the large red light 30 to be illuminated.

By means of a recording, or by means of the 40 actual voice of the engineer or fireman, announcement through the loud speaker 31 mounted on the gate cross-head, will be made as to the direction in which the train is moving.

After the train has proceeded one block electrical contact is automatically made closing the 45 circuit to the motors 8 and 9 to cause the chain barriers to unroll and drop. After the train has passed a gate the electrical circuit to the motors will be broken and the chain barriers automatically opened by being rolled up through the gravity pull of the weights 21.

As a train enters upon the system a buzzer or bell will ring in the engine cab to advise the engineer to start the recording or to himself make 50 the announcement going out over the loud speaker 31.

For the purpose of ascertaining the identity of any vehicle which engages any of the gates, I provide means of taking a moving picture of 55 said vehicle which picture will include the automobile tag and will thus enable the identification of the ownership of the vehicle.

Positioned in each roadway, slightly in advance of the gates, there is a depressible plate 60 35, which has electrical connection through the wire 36 with the aforementioned circuit wire 25 and electrical connection through a wire 37 with the electric motor 38, which motor in turn is connected to the ground wire 27 through the 70 wire 39. The depressible plate constitutes a normally open switch.

A moving picture camera is designated at 40 and driving connection is provided between the motor 38 and the speed crank of the camera. When a 75 train is two streets beyond a crossing gate, an

electric current is delivered to the depressible switch plate 35, with the result that if a vehicle is driven into contact with the gates it will pass over and cause the operation of the depressible plate switch 35 and cause the electric motor to operate the speed crank of the camera and the taking of a picture of the vehicle.

It is to be understood that there will be a camera mounted on the cross head of the gate at each side of the railroad crossing.

The current flowing in the wires 25 and 27 will be current delivered by the train or cars travelling on the railroad tracks. Suitable electric current generating means will be provided on the cars for supplying said current.

In the event a vehicle driver or pedestrian should not heed the warning given by the bells, the red lights and the loudspeaker and should enter upon the track before the gates actually close, the pedestrian and the vehicle can easily escape as the gates at either side of the track will push or swing outwardly to permit the pedestrian or vehicle to move outwardly on to the sidewalk or highway, as the case may be.

From the foregoing it will be understood that 25 an automatically operated safety gate for railroad crossings or the like is provided by the present invention. The gates at each street crossing will be automatically operated in rotation. For the purpose of delivering the current to the wires 30 suitable wire contact means will be carried by the cars for movable engagement along the wires of the sides of the railroad track.

What I claim is:

1. The combination with a highway and rail- 35 road crossing, of a rotatable support located above the said highway, a flexible gate hung and free to swing on said support, means to rotate said support to roll and unroll the said gate, and means at the lower portion of said gate automatically interlocking with the front end of a moving vehicle and by said movement elevate the front end of the said vehicle from the ground, for the purpose described.

2. In association with a highway and a rail- 45 road crossing, a rotatable support above the highway, a flexible gate having its upper end connected with the said support, means to rotate said support and roll and unroll said gate thereon to cause it to assume an open or closed position, 50 power means adapted to rotate said support to cause the gate to assume a closed position, a cable connected with a pulley attached to the said support and carrying a weight which is lifted when the gate is lowered, the lower portion of 55 the gate carrying means adapted to interlock with a moving vehicle, and said gate caused to swing when struck by the moving vehicle and to thereby lift the front end and depress the rear end of the vehicle, for the purpose set forth. 60

3. The combination with a highway and a crossing thereof, of a support above said highway, a gate hung from and free to swing on said support, means to move said gate to an open or closed position in respect to the highway, means 65 carried by said gate adjacent the lower end thereof adapted to interlock with the front end of a vehicle, said gate when struck by a moving vehicle caused to swing, and the continued swinging of said gate by said vehicle bringing the interlocking means into interlocking engagement with the vehicle, whereby the front end of the vehicle is lifted and the rear end thereof depressed, for the purpose set forth.

HARRY R. GILMORE. 75
